UNITED STATES PATENT OFFICE.

GEORGE C. JENSEN, OF OAKLAND, CALIFORNIA.

LEVER STRUCTURE AND LOCK FOR SAME.

1,271,963.

Specification of Letters Patent. Patented July 9, 1918.

Application filed February 13, 1918. Serial No. 216,965.

To all whom it may concern:

Be it known that I, GEORGE C. JENSEN, a citizen of the United States, residing at Oakland, in the county of Alameda and State of California, have invented certain new and useful Improvements in Lever Structures and Locks for Same, of which the following is a specification.

This invention relates to an improved lever construction, mounting therefor and construction for locking the same from operative movement.

The principal objects of the invention are to provide a lever capable of universal swinging movement and adapted for coöperation with suitable shifter devices and designed for operation to enable the shifter devices to be independently operated or capable of being locked to said shifter devices to prevent the operation of either or the removal of the lever support from its mounting. To provide a construction wherein the lever fulcrum and means for maintaining the lever seated in its fulcrum is simplified over those at present on the market.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

To more fully comprehend the invention reference is directed to the accompanying drawings, wherein—

Figure 1 is a view in vertical section of the preferred embodiment of my invention illustrating the same in a position for locking the shifter devices from operative movement.

Fig. 2 is a sectional view taken on the line 2—2 of Fig. 1.

Fig. 3 is a plan view of one end of the shifter devices illustrating the coöoperative flanged recesses in adjacent faces thereof.

Referring more particularly to the several views of the drawings wherein like characters of reference designate corresponding parts, 1 indicates a tubular support the base of which provides a cover attached to a

suitable housing within which are slidably mounted suitable parallel spaced longitudinally movable shifter devices 2 and 3. The shifter devices are provided at one end in their adjacent faces with coöperating recess portions 4, the upper surface of which is reduced by an overhanging flange 5. The shifter devices illustrated are of the type commonly employed in gear shift mechanism on a motor vehicle and are each adapted for independent longitudinal movement in a direction opposite from each other and from the position illustrated in Fig. 3 which is commonly termed neutral, the movement of one precluding the movement of the other thus preventing the simultaneous movement of both devices. The tubular support 1 is provided with a reduced upper end providing a flange 6 beneath which is positioned a suitable ring 7. Inserted in the support 1 is a lever body portion 8 provided intermediate of its length with a spherical portion 9 adapted to contact at its upper surface with the ring 7. A plate 10 formed centrally with an opening provided with a curved edge 11 is drawn upwardly over the lever body portion 8 from the lower end thereof and said plate slides on suitable plate guide pins 12 carried by the support 1 and extending downwardly thereinto. Suitable compression springs 13 surrounding the pins 12 and interposed between the headed ends 14 thereof on the under side of the plate maintain the plate in frictional contact with the spherical portion 9 of the lever body and said plate and ring 7 provide a fulcrum for said lever body within which the same is capable of universal swinging movement. To prevent axial rotation of the lever body on its fulcrum the same carries the laterally extending pins 15 receivable within a vertical guide slot 16 formed between the upwardly extending lugs 17 carried by the upper surface of the plate 10.

The body portion 8 of the lever is provided with a longitudinally disposed open ended bore 18 within which is mounted for axial rotation a locking bolt 19 of a length greater than said body portion 8, and said bolt at its lower end carries the oppositely disposed laterally extending arms 20, the combined length of which is substantially equal to the depth of said coöperating recesses 4 beneath the side flanges 5 thereof and also equal to the length of said recesses, 110

said arms being of a width substantially the same as the depth of one of said recesses 4. It will thus be apparent that when the locking bolt 19 is rotated to position the arms 5 20 to lie parallel with said shifter devices, that said lever is capable of lateral swinging movement to position said arms to be received within either of said recesses, and on the operative movement of the lever to 10 longitudinally move the shifter device engaged thereby, however, on the rotation of the bolt 19 to position the arms 20 at right angles to said recesses, said arms will extend into both of said recesses below said 15 flanges 5 and prevent the operative movement of the shifter device to be operated thereby, thus locking the lever from movement, as is heretofore explained the shifter devices are singly movable but in one direction from the position as in Fig. 3. When in this locked position the arms 20 lie beneath the flanges 5 and prevent the upward movement of the body portion of the lever 8, and consequently, prevent the raising of the 25 tubular support 1 from the shifter devices.

The upper end of the lever body portion 8 is preferably reduced and threaded, and attached to said upper end through a threaded connection is a lever handle portion 21 30 carrying at its lower end an enlarged portion or boss 22, said handle portion being provided with a bore 23 for registering with the bore or channel 18 of the lever body 8. Secured to the upper end of the locking bolt 35 19 is an operating head 24 carrying a laterally extending operating arm 25 which projects preferably at right angles from the handle portion 21 of the lever. The operating head 24 is provided on its surface 40 with a suitable latch receiving notch 26 adapted on the rotation of the locking bolt 19 to a position as in the drawings to register with a suitable opening 27 in the side wall of the upper end of the body portion 45 of the lever 8. The opening 27 lies in register with a bore or channel 28 formed in the boss 22 and in said channel is mounted for reciprocation a latch 29 outwardly pressed by a spring 30 for engagement within the 50 recess 26 of the head 24 and adapted to be moved inwardly against the tension of said spring by the rotation of a lock barrel 31 having an offset lower end 32 which is received in a recess 33 in the latch 29. The 55 barrel 31 is of the usual key controlled type and on the operation of the same to remove the latch 29 from the opening 25 permits the automatic axial rotation of the bolt 29 to 60 released position to position the arms 20 thereof to lie parallel with the shifter devices 3. This rotation is accomplished by the coiled spring 34 surrounding the bolt and secured at one end to the body portion 65 of the lever 8 and at its opposite end to the head 24. To prevent the entrance of dust

and grit into the fulcrum of the lever, a shell or cupped member 35 is carried by the upper end of the body portion 8 of the lever, and the same extends downwardly over the curved upper end surface 36, of the tubular 70 support 1.

Having thus described my invention what I claim as new and desire to protect by Letters Patent is:

1. In combination with a lever mounted 75 for universal swinging movement, longitudinally movable parallel spaced shifter devices coöperating therewith and adapted for independent operation on the movement of said lever, and lock controlled means depending from the lever and capable of positioning to engage both of said shifter devices, one at a point below the upper surface thereof to prevent the independent operation of the same and thus lock said lever from movement and to prevent the disengagement of the lever therefrom by an upward movement thereof. 80

2. In combination with a lever mounted for universal swinging movement, a pair of 90 longitudinally movable parallel spaced shifter devices lying beneath the same and provided on adjacent faces with coöperating depressions, lock controlled means carried by said lever and extending into said 95 depressions, said means capable of positioning to be received within one of said depressions to admit of the independent operation of said shifter devices on the movement of said lever, and of movement to extend 100 into both of said depressions to prevent the independent operation of said devices thus locking said lever from operative movement. 105

3. In combination with a lever mounted for universal swinging movement, a pair of 105 longitudinally movable parallel spaced shifter devices lying beneath the same and provided on adjacent faces with coöperating depressions, lock controlled means carried by said lever and extending into said 110 depressions, said means capable of positioning to be received within one of said depressions to admit of the independent operation of said shifter devices on the movement of said lever, and of movement to extend 115 beneath the said devices and into both of said depressions to prevent the independent operation of said devices and lock said lever from operative movement or detachment therefrom by longitudinal upward 120 movement. 115

4. In combination with a lever mounted for universal swinging movement, a pair of parallel spaced shifter devices lying beneath the same and provided on adjacent faces with coöperating depressions, means carried by said lever and extending between said devices to a point within said depression, said means capable of positioning for reception within one of said depressions to 130

admit of the independent operation of said shifter devices on the movement of said lever, and of axial rotation to extend into both of said depressions to prevent the independent operation of said devices and a lock for locking said means in its latter position.

5. In combination with a lever mounted for universal swinging movement, a pair of parallel spaced shifter devices lying beneath the same and provided on adjacent faces with coöperating depressions, means carried by said lever and extending between said devices to a point within said depression, 10 said means capable of positioning for reception within one of said depressions to admit of the independent operation of said shifter devices on the movement of said lever, and of manual axial rotation to extend 15 into both of said depressions to prevent the independent operation of said devices, a lock for locking said means in its latter position, and means for automatically restoring said means to its former position on 20 25 the release of said lock.

6. In combination with a lever mounted for universal swinging movement and precluded from axial rotation, a pair of parallel spaced shifter devices lying beneath the 30 lower end thereof and capable of independent operation by said lever, an axially rotatable locking bolt carried by and extending below said lever, said bolt provided on its lower end with laterally extending portions 35 capable of positioning to engage both of said shifter devices to lock the same from independent movement and thus preclude the movement of said lever, and lock controlled mechanism carried by the lever for 40 locking the said bolt in its latter position.

7. In combination with a lever mounted for universal swinging movement and including a body portion and an offset handle portion detachably secured thereto, said 45 body portion provided with a longitudinal bore, an axially rotatable locking bolt within said bore and provided at its upper end with an operating handle, a pair of longitudinally movable shifter devices capable 50 of independent operation on the movement of said lever, said bolt provided at its lower end with laterally extending portions adapted on the rotation of said bolt to simultaneously engage said devices to preclude

movement of said lever, and lock controlled 55 means carried by one of said lever portions for locking said bolt in its latter position.

8. In combination with a lever mounted for universal swinging movement and including a body portion and an offset handle 60 portion detachably secured thereto, said body portion provided with a longitudinal bore, an axially rotatable locking bolt within said bore and provided at its upper end with an operating handle, a pair of longitudinally movable shifter devices capable 65 of independent operation on the movement of said lever, said bolt provided at its lower end with laterally extending portions adapted on the rotation of said bolt to simultaneously engage said devices to preclude 70 movement of said lever, and lock controlled means carried by said handle portion for locking said bolt in its latter position and for locking said lever handle and body portions together.

9. In combination with a lever mounted for universal swinging movement, longitudinally movable parallel spaced shifter devices coöperating therewith and adapted 80 for independent operation on the movement of said lever, a lock controlled means associated with the lever in coöperative engagement with the shifter devices and provided with laterally extending portions, said 85 means capable of positioning to prevent the operation of said shifter devices and to lock said lever from detachment therefrom by an upward longitudinal movement thereof.

10. In combination with a lever mounted 90 for universal swinging movement, longitudinally movable parallel spaced shifter devices coöperating therewith and adapted for independent operation on the movement of said lever, lock controlled means depending from the lever in coöperative engagement with the shifter devices, said means 95 capable of positioning to prevent the operation of said shifter devices by the movement of said lever.

100 In testimony whereof I have signed my name to this specification in the presence of two subscribing witnesses.
